EXHAUST NOZZLE TIP FOR LOCOMOTIVES

Charles W. Baker, Spokane, Wash.

Application October 19, 1948, Serial No. 55,366

2 Claims. (Cl. 230—97)

This invention relates to locomotives and more particularly to an exhaust nozzle for use in the smoke box of a locomotive to create a draft for the boiler of the locomotive.

A main object of the invention is to provide a novel and improved exhaust nozzle tip for locomotives which is very simple in construction, easy to install, and which provides a smooth flow of exhaust gases through the locomotive smoke stack, thereby insuring an efficient draft for the locomotive boiler, without hazards of explosion or fire and without causing excessive back pressure to be built up in the locomotive smoke box.

A further object of the invention is to provide an improved exhaust nozzle tip for locomotives which functions to entrain exhaust gases from the locomotive boiler with exhaust steam from the locomotive engine, providing a relatively low velocity flow of gases through the locomotive smoke stack, whereby the smoke stack is completely filled instead of being partially filled as with conventional structures, whereby a more effective vacuum is created in the locomotive smoke box, and whereby the exhaust and flow of gases upwardly through the stack will be smoothly controlled, avoiding the explosive action produced by the conventional nozzle tip.

Further objects and advantages of the invention will become apparent from the following description and claims, and from the accompanying drawings, wherein:

Figure 1 is a fragmentary side elevational view, partly in cross-section of the forward portion of a locomotive provided with an exhaust nozzle constructed in accordance with the present invention.

Figure 2 is a cross-sectional detail view taken on line 2—2 of Figure 1.

Figure 3 is an enlarged top plan detail view of the exhaust nozzle employed in Figure 1.

Figure 4 is a cross-sectional view taken on line 4—4 of Figure 3.

Figure 5 is a cross-sectional view taken on line 5—5 of Figure 4.

Referring to the drawings, 11 designates a conventional locomotive having at its forward end the usual smoke box 12 into which the boiler tubes 13 discharge, said smoke box being provided with the smoke stack 14 extending through its top wall for discharge of the gaseous products of combustion and for creating the draft required by the boiler. Designated generally at 15 is the steam exhaust nozzle which conveys the exhaust steam from the engine cylinders 16 of

the locomotive into the smoke box, said nozzle being positioned below the smokestack 14 and in axial alignment therewith. In the conventional locomotive, the nozzle is constructed so as to furnish jets of steam upwardly into the smokestack, creating an accelerated flow by expansion of the steam whereby the exhaust gases are drawn upwardly through the stack in intermittent pulses, discharging said gases at relatively high velocity and creating a pulsing draft through the fire box of the locomotive.

In accordance with the present invention the nozzle 15 comprises an upwardly convergent elongated intake portion 17 having a top flange 18. Designated at 19 is a generally cylindrical throat portion having a bottom flange 20 which is secured to flange 18. The upper end of throat portion 19 is open and provides a relatively large discharge orifice which is only slightly reduced with respect to the inside area of throat member 19 by an internal lip 21, thereby providing only a slight throttling action at said orifice when steam escapes therefrom. Secured to the top end of throat member 19 by a plurality of outwardly projecting radial arms 22 is a downwardly flaring conical hood 23 overlying the top end of the throat member 19 but being spaced therefrom. As shown in Figures 3 and 4, the top orifice 24 of hood 23 is substantially larger than orifice 21 and is vertically spaced above the orifice 21, and is smaller in diameter than the lower end of the stack 14, as shown in Figures 1 and 2. The hood 23 defines an annular upwardly convergent passage 25 with respect to the outer surface of throat member 19.

In operation, the exhaust steam flows upwardly in intake portion 17 and is slightly compressed in throat portion 19. The exhaust steam escapes upwardly through orifice 21 into hood 23 with a moderate throttling action. This throttling action in hood 23 produces a slight acceleration in the upward movement of the exhaust steam with a reduction in pressure in the upper portion of hood 23 sufficient to draw exhaust gases from the boiler tubes 13 upwardly through the annular convergent passage 25. The exhaust gases are entrained with the upwardly moving steam in the upper portion of hood 23 and the mixture is then discharged through the top orifice 24 of the hood, again with a slight throttling action. The mixture of exhaust gas and steam flows upwardly into the smokestack 14, and since the mixture is moving at only a moderate velocity, the smokestack is substantially filled with the upwardly moving mixture of fluids. As a re-

sult, the discharge from the top of the smoke-stack is substantially continuous instead of intermittent and a constant vacuum is developed in the smoke box 12, said vacuum producing a constant draft through the locomotive fire box without building up back pressure in the smoke box.

The smoke box is provided with a suitable wire mesh spark arrester 26 having a portion 27 thereof extending across the smoke-stack 14 to prevent the discharge of sparks from the smoke stack.

While a specific embodiment of an improved exhaust nozzle tip for locomotives has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In combination, a locomotive smoke box including a stack rising from the top of the smoke box and having an open lower end in the upper part of the smoke box, an exhaust nozzle positioned in the lower part of the smoke box in axial alignment with said stack, said exhaust nozzle comprising an upwardly tapered tubular intake portion having an open upper end and a lower end adapted to intake exhaust steam from the locomotive, a uniformly cylindrical open-ended tubular throat portion mounted axially on the upper end of said intake portion, said throat portion being of the same diameter as the upper end of said intake portion, and an upwardly converging conical hood surrounding said throat portion and mounted thereon, said hood having an open upper end larger in diameter than said throat portion and smaller in diameter than the lower end of the stack end spacedly surrounding said throat portion, the lower end of said hood being substantially larger in diameter than the lower end of the stack, the lower end of the hood being open and positioned on a level below the open upper end of said throat portion, the upper end of said hood being spaced at a substantial distance below the lower end of said stack.

2. In combination, a locomotive smoke box including a stack rising from the top of the smoke box and having an open lower end in the upper

part of the smoke box, an exhaust nozzle positioned in the lower part of the smoke box in axial alignment with said stack, said exhaust nozzle comprising an upwardly tapered tubular intake portion having an open upper end and a lower end adapted to intake exhaust steam from the locomotive, a uniformly cylindrical open-ended tubular throat portion mounted axially on the upper end of said intake portion, said throat portion being of the same diameter as the upper end of said intake portion, and an upwardly converging conical hood surrounding said throat portion and mounted thereon, said hood having an open upper end larger in diameter than said throat portion and smaller in diameter than the lower end of the stack end spacedly surrounding said throat portion, the lower end of said hood being substantially larger in diameter than the lower end of the stack, the lower end of the hood being open and positioned on a level below the open upper end of said throat portion, the upper end of said hood being spaced at a substantial distance below the lower end of said stack, the upper end of said throat portion being formed with an internal annular lip providing a slight reduction of the internal diameter of said throat portion at its upper end.
